UNITED STATES PATENT OFFICE.

ISHAM RANDOLPH, OF RIVERSIDE, ILLINOIS, ASSIGNOR TO THE LINK-BELT MACHINERY COMPANY, OF CHICAGO, ILLINOIS.

CONVEYER.

SPECIFICATION forming part of Letters Patent No. 665,267, dated January 1, 1901.

Application filed April 19, 1900. Serial No. 13,434. (No model.)

To all whom it may concern:

Be it known that I, ISHAM RANDOLPH, a citizen of the United States, residing at Riverside, in the county of Cook and State of Illinois, have invented a new and useful Improvement in Conveyers, of which the following is a specification.

My invention consists of an improved conveyer, possessing special value as a means for moving or transporting freight or passengers comparatively short distances.

My object is to provide a laterally-flexible conveyer capable of moving upon curves or in an endless path while maintaining an even or unbroken top surface.

In the accompanying drawings, Figure 1 is a plan view showing my improved conveyer in the form of a traveling endless platform; Fig. 2, an enlarged broken plan view of a section of said platform; Fig. 3, a view, partly in side elevation and partly in section, of a portion of the platform; Fig. 4, a cross-section at line 4 of Fig. 2; Fig. 5, a broken plan view showing the junction of two segments of a flexible connecting-bar employed; Fig. 6, details of the connection at the joint; Fig. 7, a plan view showing segments of the platform mounted on trucks of tricycle form; Fig. 8, a view in side elevation of the same, and Fig. 9 a view taken as indicated at line 9 of Fig. 8.

As appears from Figs. 3 and 9, the conveyer may be mounted in various ways, and it will be understood, readily, that any suitable driving mechanism may be employed.

In Figs. 1 to 4, inclusive, I have shown the conveyer supported on casters moving on rails in a channel below the level of a floor or stationary platform and driven by sprocket-wheels.

In Figs. 7 to 9, inclusive, the conveyer is shown arranged to move in a similar channel, the mounting being changed to trucks running upon suitable rails, it being understood that any desired means for propulsion may be employed.

In the preferred form alternate convex segments or disks A and concaved segments A', suitably articulated, are employed. The lateral edges of each concaved segment are substantially tangential to the disks between

which it is located. In Figs. 2 and 3 the disks A are shown provided with tongues or feathers a, which fit into grooves in the concave edges of the segments A'. In Figs. 7 to 9 the disks are shown provided with lower horizontal flanges b, upon which rest upper flanges b' of the segments A'.

By preference each disk or segment A is supported to turn in a horizontal plane. In the first figures of the drawings each disk is shown supported by a central long-stemmed caster c, moving on a rail B, and two flanking short-stemmed casters c', moving on rails B', and each concaved segment A' is shown supported by short-stemmed casters c'', moving on rails B''. Upper and lower connecting-bar segments C and C' join the stems of the casters c. Alternate bar-segments are provided at their lower edges with pivot heads d, and the remaining alternate segments are provided at their upper edges with similar heads d', said heads serving to receive the caster-stems and admitting, by reason of the alternate arrangement described, all the segments of a given bar to lie in one horizontal plane. The bar C' is supported by collars f, the bar C by collars f', and the disks A by collars f''. The bar-segments are preferably of T-iron with flange uppermost, and those segments receiving the heads d' have their flanges removed far enough to receive the top surfaces of said heads flush with the top surfaces of the flanges. The disks and segments A and A' are provided with chafing-plates f''' and f''', which bear upon the upper connecting-bar. Horizontally-disposed wheels D and D' may serve to drive the conveyer through the medium of prongs g, separated by chords of the same length as the connecting-bar segments and which engage the stems of the central casters c.

E may represent the floor of a freight or ware house or it may represent any stationary platform provided with a channel E' for the conveyer.

Referring again to Figs. 7 to 9, inclusive, the disks A are shown supported by brackets h, projecting from bolsters h', carried by blocks h'', journaled on axles h'', connecting the main truck-wheels h''. The wheels h'' are flanged after the manner of car-wheels and

travel on side rails h^5 . Each truck is provided with a grooved guide-wheel h^6 , which runs on a central guide-rail h^7 . The trucks are connected by bar-segments C of the form already described, a pivotal stud h^8 (indicated in dotted lines) passing through disk, heads d and d' , and into bolster h , serving to connect adjacent connecting-bar segments.

Any form of motor may be employed to 10 propel the conveyer, and it is not indispensable that the conveyer be endless. Also it is not regarded as absolutely essential that a disk be articulated with each adjacent concaved segment A' . Thus any disk A may be 15 selected, and the segment A' at either side thereof may be regarded as rigid with said disk. Continuing in the direction chosen, each disk encountered may be considered as rigidly joined to the segment A' in advance 20 thereof. It therefore appears that the indispensable condition necessary to make the conveyer operative is that there shall be alternate platform-segments each having at least one circular concavity and alternate platform-segments each having at least one circular convexity to fit into a concavity. 25

It will be observed that the edges of the platform are practically continuous or unbroken, the segments being of a uniform 30 width, practically equal to a diameter of a disk. Thus a cross-section of the platform at any point has the same length as at any other point regardless of curves. The platform is left open and uninclosed—that is, 35 without cover and sides—so that articles may be loaded or removed at any point.

What I claim as new, and desire to secure by Letters Patent, is—

1. In a laterally-flexible endless conveyer, 40 the combination of sets of flat uninclosed segments affording a movable open platform, each segment of one set having at least one convexity and each segment of the other set at least one concavity to receive a convexity, 45 mountings for said segments, and flexible connecting means, substantially as and for the purpose set forth.

2. In a conveyer, the combination of disks A and concaved segments A' alternating 50 therewith to form a flexible platform of continuous surface, connecting-bar segments joining disk-centers, and mountings for the flexible platform, substantially as and for the purpose set forth.

3. In a conveyer, the combination of segments forming a flexible platform having continuous surface, mounted supports for alternate segments, central pivotal studs for said last-named segments, connecting-bar segments joining said studs, and supporting means for the intermediate segments, substantially as and for the purpose set forth.

4. In a conveyer, the combination of disks A, central studs for the several disks, connecting-bar segments joining said studs, concaved segments A' alternating with said disks, and mountings for the laterally-flexible plat-

form thus formed, substantially as and for the purpose set forth.

5. In an endless conveyer, the combination 70 of articulated segments forming a laterally-flexible platform of continuous surface and of uniform width, connecting-bar segments joining the platform-segments, and mountings for the flexible conveyer thus formed, 75 substantially as and for the purpose set forth.

6. In a conveyer, the combination of articulated segments forming a laterally-flexible platform of unbroken surface, trucks for alternate segments having oppositely-located 80 track-wheels supporting said segments, guide-wheels for said trucks, and bar-segments, pivotally joined to adjacent trucks, substantially as and for the purpose set forth.

7. An endless platform movable in a horizontal plane comprising joined platform-sections the meeting edges of which abut throughout and maintain an unbroken top surface regardless of lateral movement. 85

8. A platform-carrier, comprising an endless flexible power-transmitting device, a series of supporting devices connected thereto, a part fixed to each supporting device, and intermediate abutting parts movably connected to the supporting devices so as to form 95 a substantially continuous even surface for the carrier, said abutting parts provided with curved abutting faces which permit their relative movement without varying the distance between them. 100

9. A platform-carrier, comprising a series of sections having substantially flat upper surfaces and lying in substantially the same horizontal plane, a connecting and driving device to which the several sections are attached, 105 said sections curved at their meeting ends and opposed to each other, so that such sections can swing in the horizontal plane with reference to each other without varying materially the distance between their opposed edges.

10. In a platform-conveyer, the combination of sections having curved ends with segments having curved ends alternating therewith to form a flexible platform of continuous surface, connecting-bar segments joining section-centers, and mountings for the flexible platform and a locally-fixed driving mechanism, substantially as and for the purposes 115 set forth.

11. In a platform-conveyer, the combination of sections A, central studs for the several sections, connecting-bar segments joining said studs, concaved segments alternating with said sections and mountings for the laterally-flexible platform thus formed and a locally-fixed driving mechanism. 125

12. A platform movable in a horizontal plane, comprising joined platform sections or segments, the meeting edges of which abut throughout and maintain an unbroken top surface regardless of lateral movement and a locally-fixed driving mechanism. 130

13. A carrier, comprising a flexible power-

transmitting device, a series of supporting devices connected thereto, a part fixed to each supporting device, and intermediate abutting parts movably connected to the supporting device so as to form a substantially continuous even surface for the carrier, said abutting parts provided with curved abutting faces, which permit their relative movement without varying the distance between them and a locally-fixed driving mechanism.

14. A platform-carrier, comprising a series of sections having upper surfaces, the abutting portions of which lie in substantially the same horizontal plane, a connecting and driving device to which the several sections are attached, said sections curved at their meeting ends and opposed to each other, so that such sections can swing in the horizontal plane with reference to each other, without varying materially the distance between their opposed edges and a locally-fixed driving mechanism.

15. A platform-carrier, comprising a series of sections, a connecting and driving device to which the several sections are attached, said sections curved at their meeting ends

and opposed to each other, so that such sections can swing in the horizontal plane with reference to each other, without varying materially the distance between their opposed edges and a locally-fixed driving mechanism. 30

16. A platform-like carrier, comprising a series of sections, locally-fixed means for driving the sections, said sections curved at their meeting ends and opposed to each other, so that they can swing in the horizontal plane 35 with reference to each other, without varying materially the distance between their opposed edges.

17. A platform-like carrier, comprising a series of sections arranged to form an endless 40 platform, means for driving the sections, said sections curved at their meeting ends and opposed to each other, so that they can swing in the horizontal plane with reference to each other, without varying materially the distance 45 between their opposed edges.

ISHAM RANDOLPH.

In presence of—

ARTHUR BROWNING,
W. T. NORTON.
